PASQUALE GALASSI, OF NEW YORK, N. Y.

METHOD OF PRODUCING DIVIDING STRIPS FOR FLOORS

Application filed March 5, 1930. Serial No. 433,315.

This invention relates to terrazzo and similar floors and more particularly refers to improvements in methods of production of dividing strips such as are ordinarily used in

5 the type of floors mentioned.

Terrazzo, granolithic, stucco and similar floors usually comprise a lower or foundation bed made of concrete or cement or mortar or other suitable material, and an upper or 10 finishing layer generally consisting of a mixture of marble chips and cement, by means of which a good durable surface may be obtained as well as pleasing designs and color effects of a practically unlimited variety.

15 The upper layer which is generally placed in position after the foundation layer has been allowed to harden to a sufficient degree of consistency, is generally divided into a number of panels or units in a predetermined 20 arrangement, which are obtained by outlining the desired design by means of dividing strips placed on or through the foundation layer.

25 These strips generally consist of relatively thin and wide metal bars set on edge, said bars having their upper edges flush with the surface of the floor, forming the desired design; said bars being generally provided with anchoring and positioning means insuring 30 a firm binding action between the strips and the materials of which the floor is composed.

These bars are generally made of relatively soft metal such as brass for instance, the 35 wearing qualities of which are approximately equal to those of the floor itself; and according to the nature of the floor and of the design to be produced, the dividing strips may be of various thicknesses and lengths.

40 Relatively thin strips may readily be obtained out of sheet metal, and are suitable for floors of moderate size; however, relatively large floors, or floors composed of relatively large units, call for strips having sufficient rigidity to withstand the lateral pressure of 45 the material without bulging when the floor is laid.

These heavier strips are also generally made out of sheet metal but brass being expensive material, their use materially increases the cost of the floor. At times the

ornamental features are such as to require extra thick metallic strips showing through the material, and in these cases, the cost is still higher.

In another copending application entitled 55 "Floor strips", Ser. No. 375,052, I have described and claimed a type of dividing strip the construction of which is such as to materially reduce the cost of a floor without impairing its appearance, said strip comprising 60 a continuous upper portion having an uninterrupted upper edge and a lower portion composed of longitudinally spaced lugs depending from the upper portion.

The present invention has for its main object to provide a method of producing strips of the type to which said other copending application refers making it possible to produce two dividing strips out of a single wider metal strip by the expenditure of a relatively 65 small amount of labor, said method of production also making it possible to use the material with a maximum of efficiency.

Another object of this invention is to provide a method of making dividing strips for 75 terrazzo or like floors, making it possible to produce two full width dividing strips out of a single metal strip the width of which is less than twice the width of each dividing strip.

80 A further object of the invention is to provide a novel and improved method of making dividing strips of the character specified, whereby reinforcing or anchoring means or both are produced in a blank metal strip before said blank strip is divided along a zig-zag or substantially undulating line to produce two dividing strips without any waste of material.

85 Other objects and advantages of the present invention will more fully appear as the description proceeds and will be set forth and claimed in the appended claims.

The invention is illustrated by way of example in the accompanying drawings, in 95 which:

Fig. 1 is a fragmentary plan view of a strip blank illustrating the method of producing two strips of the type to which my invention refers, said strips being provided with 100

anchoring means and with a reinforcing rib member;

Fig. 2 is a cross sectional view of the same through line 2—2 of Fig. 1; and

Fig. 3 is a fragmentary plan view of a strip blank illustrating the method of producing therefrom two strips each provided with a reinforcing rib member, the lugs of said strips having outwardly inclined edges and being therefore adapted to fulfill the function of anchoring means.

Referring to Figs. 1; 2 it will be seen that two identical dividing strips 39, 39' are obtained out of a single strip blank, the width of which is equivalent to the height a' of a single strip plus the height b' of the upper section of the other strip. Each strip is formed with a longitudinal reinforcing bead 40, 40' and anchoring means such as 41, 41' are struck off the lugs 42, 42' forming the lower portion of each strip.

Each strip comprises an upper portion 11 having an uninterrupted upper edge 12, and a plurality of spaced lugs 13 depending therefrom, said lugs having their lower edges 14 in alignment with one another and parallel to the upper edge 12. Said lugs are preferably spaced at even intervals and have a width equivalent to one-half the distance between adjoining lugs, thus forming intervening notches or recesses, the width and height of which correspond to the width and height of the lugs. By virtue of this construction, it becomes possible for similar lugs 35 of another strip to interextend within said notches as the drawings show. It is therefore possible to produce two full width strips out of a strip blank the width of which is only equal to the height of a single strip plus the height b' of the upper section of another strip. In practice the height of the upper section is only from 40 to 50% of the total height of the strip, so that the resulting saving in metal is from 25 to 30%. The lugs are 45 preferably made wide enough to permit anchoring means being laterally off-set therefrom, said anchoring means being preferably also adapted to act as positioning means. To make this matter clear, it is well to state that 50 the strips should preferably be anchored into the floor material in order to prevent their coming loose; and that the function of the positioning means is to act as a gauge for the laying of the foundation layer, consequently 55 determining at the same time the thickness of the upper or finishing layer.

In Fig. 3 I illustrate the possibility of making two dividing strips 43, 43' out of a single strip blank, said strips having their lower portion consisting of longitudinally spaced lugs 44, 44' having a dovetailed or equivalent outline causing their end edges to be outwardly inclined from top to bottom.

By virtue of this construction, the lugs 65 themselves can fulfill the function of anchor-

ing means due to the interlocking action taking place between the lugs and the floor composition, so that there is no necessity of providing additional anchoring means in the form of lugs or ears or cup members struck off the body of the strip.

The strips thus provided are preferably formed with longitudinal rib members 45, 45', if light gauge metal is employed; it being understood that the provision or not of these rib members is a matter of choice, this feature being omitted when the gauge of the metal used is such as to provide sufficient rigidity.

It is not necessary for the strips thus produced to have their lugs symmetrical with the notches intervening therebetween, nor is it necessary that the two strips produced out of a single blank be identical as long as they are complementary to each other so as to permit of using a minimum quantity of metal with a maximum of efficiency.

The method of producing these strips or sections of strips is illustrated in the drawings. If the strips to be produced are not formed with any rib or bead member and are devoid of anchoring means struck off from the body of the strip as would be the case for instance in connection with strips of the type shown in Fig. 3, minus the bead member 45, 45', the method of production is limited to 95 a single operation, that is, the cutting off of the strip blank along the zigzag line such as indicated at 53 in Fig. 3.

If the two strips have to be formed with a rib member such as beads 45, 45', I prefer to 100 form the two beads first and then divide the strip blank along the zigzag line 53 as shown. In this case, the width of the strip blank will, of course, be somewhat greater than if no beads are to be formed out of the body of metal. I prefer to form the beads first as 105 stated, because the pressure exerted against the strip blank can thus be easily balanced so that no deformations of its edges occur.

Furthermore, it is possible and at times it 110 may be preferable to form said beads by means of rollers instead of by means of embossing dies.

When anchoring means such as shown in Figs. 1 and 2 have to be provided, said anchoring means are also struck off the body of the strips and bent outwardly before the strip blank is divided into the two strips, and if bead members such as 40, 40' are produced then the anchoring means are formed 115 after the rib or bead members have been produced and before the strip blank is divided into the two strips.

The sequence of operations mentioned are advocated in conformity with what is deemed to be best practice, but it will be understood that they do not exclude the possibility of dividing the strip blank into two strips before performing the remaining operations.

By virtue of the method of production ad- 130

vocated there is absolutely no waste of material, so that a considerable economy may be effected in the cost of production as against strips of equivalent height having both edges 5 of an uninterrupted character.

Strips of numerous other designs could be illustrated all embodying my inventive idea which consists substantially in economically producing a strip of standard height provided or not with anchoring or positioning means and possessing sufficient rigidity without using as much metal as is now employed for similar products.

The drawings are intended for illustrative 15 purposes only and not in a limiting sense; I therefore reserve myself the right to carry my invention into practice in all those ways and manners which may enter, fairly, into the scope of the appended claims.

20 I claim:

1. The method of making dividing strips for terrazzo floors or the like, which consists in forming longitudinal reinforcing members intermediate the side edges of a strip and the 25 center thereof, and then subdividing said strip longitudinally and intermediate the reinforcing members thus produced along a longitudinal zigzag dividing line whereby to form two strips having an uninterrupted edge and a plurality of projections and recesses along the 30 opposite edge.

2. The method of making dividing strips for terrazzo floors or the like, which consists in forming longitudinal reinforcing members 35 intermediate the side edges of a strip and the center thereof, and then subdividing said strip longitudinally and intermediate the reinforcing members thus produced along a longitudinal zigzag dividing line whereby to form two 40 identical strips having an uninterrupted edge and a plurality of projections and recesses along the opposite edge.

3. The method of making dividing strips for terrazzo floors or the like, which consists 45 in forming longitudinal reinforcing members intermediate the side edges of a strip and the center thereof, and then subdividing said strip longitudinally and intermediate the reinforcing members thus produced along a 50 longitudinally symmetrical zigzag dividing line whereby to form two identical strips having an uninterrupted edge and a plurality of homologous projections and recesses along the opposite edge.

55 4. The method of making dividing strips for terrazzo floors or the like, which consists in forming longitudinal reinforcing members intermediate the side edges of a strip and the center thereof, punching out of the strip a 60 plurality of longitudinally spaced anchoring members, and subdividing said strip longitudinally and intermediate the reinforcing members thus produced along a longitudinal zigzag dividing line, having its transversal 65 tracts passing between adjoining anchoring

members, whereby to form two self anchoring strips having an uninterrupted edge and a plurality of projections and recesses along the opposite edge.

5. The method of making dividing strips for terrazzo floors or the like, which consists in forming longitudinal reinforcing members intermediate the side edges of a strip and the center thereof, punching out of the strip a plurality of longitudinally spaced anchoring members, and subdividing said strip longitudinally and intermediate the reinforcing members thus produced along a longitudinally symmetrical zigzag dividing line having its transversal tracts passing between adjoining anchoring members, whereby to form two identical self anchoring strips having an uninterrupted edge and a plurality of homologous projections and recesses along the opposite edge.

70 6. The method of making dividing strips for terrazzo floors or the like, which consists in forming longitudinal reinforcing beads intermediate the side edges of a strip and the center thereof, and then subdividing said strip longitudinally and intermediate the reinforcing beads thus produced along a longitudinal zigzag dividing line whereby to form two strips having an uninterrupted edge and a plurality of projections and recesses along the opposite edge.

75 7. The method of making dividing strips for terrazzo floors or the like, which consists in forming longitudinal reinforcing beads intermediate the side edges of a strip and the center thereof, and then subdividing said strip longitudinally and intermediate the reinforcing beads thus produced along a longitudinally symmetrical zigzag dividing line whereby to form two identical strips having an uninterrupted edge and a plurality of homologous projections and recesses along the opposite edge.

80 8. The method of making dividing strips for terrazzo floors or the like, which consists in forming longitudinal reinforcing beads intermediate the side edges of a strip and the center thereof, punching out of the strip a plurality of longitudinally spaced anchoring members, and subdividing said strip longitudinally and intermediate the reinforcing beads thus produced along a longitudinally symmetrical zigzag dividing line having its transversal tracts passing between adjoining anchoring members, whereby to form two identical self anchoring strips having an uninterrupted edge and a plurality of homologous projections and recesses along the opposite edge.

85 9. The method of making dividing strips for terrazzo floors or the like, which consists in forming longitudinal reinforcing members intermediate the side edges of a strip and the center thereof, and subdividing said strip longitudinally and intermediate said rein-
